PARACHUTE

Peter J. Swofford, Arlington, Tex.

Application February 10, 1938, Serial No. 189,881

4 Claims. (Cl. 244—142)

This invention relates to parachutes and has for one of its objects the production of a simple and efficient parachute wherein a hollow band is provided around which the parachute or parachute portions are arranged in a manner to provide a maximum amount of buoyancy and also in a manner to minimize the danger of entanglement of the guy webs or cords.

A further object of this invention is the production of a simple and efficient parachute having a collapsible and expandible central body portion to which the various parachute portions are secured in a manner to facilitate the attachment of the ends of the guy webs at the circumference of a relatively large circular band formed around the body thereby minimizing the danger of the entanglement of the guy webs while the parachute is opening.

Other objects and advantages of the present invention will appear throughout the following specification and claims.

In the drawings:

Figure 1 is a side elevational view of the parachute in an extended or open position;

Figure 2 is an enlarged vertical sectional view with certain parts in side elevation, through the parachute certain parts being broken away;

Figure 3 is a transverse sectional view taken on line 3—3 of Figure 2;

Figure 4 is a fragmentary side elevational view of a portion of the body looking at the inner face of one of the air vent valves;

Figure 5 is a vertical sectional view taken on line 5—5 of Figure 4;

Figure 6 is a side elevational view of a modified form of the invention showing a single parachute portion of the umbrella type carried by the body of the parachute.

By referring to the drawings, it will be seen that 10 designates the body of the parachute which preferably comprises an elongated fabric tube closed at its upper end 11, and having an open lower end 12. This body 10 is provided with a plurality of transversely extending spaced reinforcing fabric bands 13 extending circumferentially around the body 10, as shown in the drawings, and the body 10 is also provided with spaced longitudinally extending reinforcing fabric bands 14 which may be secured in any suitable or desired manner to the fabric tubular body 10.

A pilot chute of suitable design indicated by the numeral 15 is preferably secured to the upper closed end 11 of the body 10 and this pilot chute 15 is preferably secured to the upper closed

end 11 of the tubular body 10 by suitable fabric guy webs 16. Any suitable type of pilot means, however, might be employed for accomplishing the desired purpose without departing from the spirit of the invention.

In carrying out my invention, I preferably provide an upper parachute portion of the umbrella type indicated by the numeral 17, and intermediate parachute portion 18, and a lower parachute portion 19, which are arranged one above 10 the other and which encircle the tubular body 10. Any suitable number of these parachute portions might be employed without departing from the spirit of the invention. The parachute portions 17, 18 and 19 are all similarly constructed and 15 it is thought necessary only to describe the detail structure of one parachute portion and that parachute portion designated by the numeral 17 will be specifically described.

The parachute portion 17 is secured, as shown 20 in Figure 2, to the outer face of the tubular body 10 near its upper end 11 by means of a fabric band or other suitable securing means 20, and this parachute portion 17 is provided with a plurality of radiating fabric reinforcing bands constituting ribs 21 preferably secured to the outer face of the parachute portion 17. These bands 21 extend beyond the outer periphery 22 of the parachute portion 17 to provide fabric guy webs 23, which fabric guy webs 23 are firmly secured 25 to any suitable or desired manner at their ends 24 to a circular fabric band 25 which circular fabric is firmly secured in any suitable manner to the outer face of the hollow tubular body 10. The band 25 is fixed to the body and expands 30 and contracts therewith. The detail parts of the parachute portions 18 and 19 are designated by similar numerals as those used in connection with the parachute portion 17 with the addition of the coefficient "a" in connection with parachute portion 18, and the addition of the coefficient "b" used in connection with the portion 19.

It will be noted that the circular web band 25 of the portion 17 is secured to the tubular 45 body 10 at a point adjacent the upper end of the parachute portion 18, and the circular web portion 25a of the parachute portion 18 is secured to the tubular body portion 10 near the upper end of the parachute portion 19. The circular web band 25b of the parachute portion 19 is firmly secured around the lower open end of the hollow tubular body 10—note particularly Figures 1 and 2. A suitable harness 26 is suspended from the lower end of the tubular body 50 55.

10 as shown in the drawings. The fabric web or webbing described above is preferably of the flat fabric web type although cords may be employed without departing from the spirit of the invention. It is found preferable, however, that fabric webbing be employed for the reason that such material is not likely to become entangled and tends to lie flat both when packed, as well as when in an extended position.

15 In order that the expansion of the hollow fabric tubular body 10 may be facilitated, I preferably provide a plurality of spaced apertures 27 within the length of the body 10 which apertures are preferably elliptical in shape having their longest axes extending transversely of the body. Fabric valve flaps 28 are stitched or otherwise secured to the inner face of the body 10, as shown in detail in Figure 5, these flaps 28 being preferably stitched to the body along the bottom edge 29 and end edges 30, the upper edge being left free and these valve flaps 28 overlie the apertures 27 in the manner shown in Figure 5, thereby permitting air to pass in the direction of the arrows through the apertures 27 and into the interior of the hollow tubular body 10. This action will cause the hollow tubular body to expand or to open when the parachute is released in a conventional manner, and as the air catches under the edge 22 of the upper parachute portion 17, while the parachute is in the process of opening the body will also be further expanded or opened from a collapsed to an extended position. As the successive parachute portions 17, 18 and 19 open fully to the extended position, and the body 10 is also extended or fully opened from a collapsed to a fully extended tubular formation, the air pressure within the hollow tubular body 10 being greater than the air pressure without due to the fact that the air will be confined within the hollow tubular body 10, will cause the valve flaps 28 to close tightly over the inner faces of the valve openings 27 and prevent the escape of air therethrough, in this way adding greatly to the buoyancy of the parachute.

45 In Figure 6, I have shown a modified type of my invention illustrating a single parachute portion and by carefully considering Figure 6, it will be seen that 31 designates the hollow collapsible tubular body having a closed upper end 32 to which is secured a pilot parachute portion 33, the lower end of the tube 31 being open, as at 34, from which open lower end is suspended a conventional harness 35. The tubular body 31 is 50 preferably reinforced in a manner similar to that previously described with respect to Figure 1 through the medium of the longitudinally extending reinforcing web portions 36 and the transversely extending portions 37. A parachute portion 38 of the umbrella type, is secured at its upper end, as at 39, to the body 31 and carries radiating reinforcing webs or ribs 40, the ends of which extend beyond the outer periphery of the parachute portion 38 and constitute guy webs 41 which are connected to the circular band 42 carried by the lower open end of the body 31 in a manner similar to that described with respect to the structure shown in Figure 1.

70 One of the important features of the present invention is the fact that the parachute is so constructed as to constitute a hollow tubular body portion which may be expanded or extended automatically from a collapsed to an open position by the action of air passing into the hollow tubular body moving and expanding the con-

necting band to which are secured the guy webs, thereby supporting the guy webs at their inner ends around the circumference of a circle and not having a common central point as is usual with parachutes of the general type illustrated 5 and described. This arrangement will greatly minimize the possibility of entanglement of the guy webs and the construction and arrangement illustrated and described will provide a reinforced 10 parachute construction of maximum strength and durability and at the same time provide a parachute which will not possess excessive weight.

15 It of course should be understood that the size of the parachute portions 17, 18 and 19, or the 20 parachute portion 38, which constitute wings, and the distance of spacing, will depend largely upon the number of parachute units or portions used and the weight to be carried. The guy webs or shroud cords because of their particular arrangement, as illustrated and described, will prevent 25 the shroud cords and webs from becoming entangled, and the arrangement of these webs or bands will provide a sturdy chute which will not be likely to side-slip or whip-crack the pilot or person being supported upon the parachute. Furthermore, 30 the particular arrangement will facilitate the packing and shipping, and will eliminate excessive weight.

35 It should be understood that certain detail changes in the construction may be employed 30 without departing from the spirit of the invention, so long as such changes fall within the scope of the appended claims.

Having described the invention, what I claim as new is:

1. A parachute of the class described comprising 35 an elongated hollow tubular collapsible fabric body, a plurality of superimposed parachute portions of an umbrella type carried by the body and circumferentially and exteriorly mounted 40 thereon, bracing means secured to the parachute portions and also to the exterior of the body adjacent the adjoining parachute portion, said body having apertures formed therein for the admission of air through the sides of the body to the 45 interior of the body, and upwardly opening valve flaps secured to the inner face of the body adjacent the apertures and adapted to normally close the apertures when pressure from within the body exceeds pressure from without the body. 50

2. A parachute of the class described comprising 55 an hollow collapsible tubular body closed at its upper end and open at its lower end whereby air may be admitted into the body through the lower end for automatically expanding the body 60 from a folded and collapsed position to an extended position, and a parachute portion carried by the body and exteriorly surrounding the body intermediate the ends of the body whereby one portion of the tubular body extends above and another portion of the body extends below the 65 parachute portion to provide a stabilizing means for the parachute portion when the body and 70 parachute portion are extended.

3. A parachute of the class described comprising 65 an hollow collapsible tubular body closed at its upper end and open at its lower end whereby air may be admitted into the body through the lower end for automatically expanding the body 70 from a folded and collapsed position to an extended position, a parachute portion carried by the body and exteriorly surrounding the body intermediate the ends of the body whereby one portion of the tubular body extends above and another portion of the body extends below the 75

parachute portion to provide a stabilizing means for the parachute portion when the body and parachute portion are extended, said body having vent openings located directly under the 5 parachute portion and shielded thereby, and means cooperating with said vent openings and adapted to fit thereover for automatically closing the openings when pressure within the body exceeds pressure from without the body.

10 4. A parachute of the class described comprising an elongated hollow tubular collapsible fabric body, a plurality of superimposed parachute por-

tions of an umbrella type carried by the body and circumferentially and exteriorly mounted thereon, said tubular body extending above and below all of the parachute portions, bracing means secured to the parachute portions and also to the exterior of the body adjacent the adjoining parachute portion, and said body having valve means for controlling the entrance of air into the body, said valve means being adapted to automatically close when pressure within the body exceeds pressure from without the body. 10

PETER J. SWOFFORD.
